UNITED STATES PATENT OFFICE.

JOSEPH H. ZENS, OF MILWAUKEE, WISCONSIN.

KNITTING MACHINE.

Application filed October 9, 1922. Serial No. 593,231.

To all whom it may concern:

Be it known that I, JOSEPH H. ZENS, a citizen of the United States, residing at Milwaukee, in the county of Milwaukee and State of Wisconsin, have invented certain new and useful Improvements in Knitting Machines, of which the following is a specification, reference being had to the accompanying drawing, forming a part thereof.

This invention relates more particularly to means for producing seamless hosiery or the like, with reinforcements comprising portions of different widths; the objects of this invention being to provide circular knitting machines of a standard or well known type with means for knitting splicing or reinforcing yarn with the main yarn into seamless hosiery in partial courses of different lengths, to form a reinforcement such as a high splice heel reinforcement, comprising a narrower upper portion and a wider lower portion next to the heel, as shown, for example, in United States Letters Patent No. 1,169,416, dated January 25, 1916.

It consists in the construction, arrangement and combination of parts as herein-after particularly described and pointed out in the claims.

In the accompanying drawing like characters designate the same parts in the several figures.

Figure 1 is a vertical section of a portion of a circular knitting machine in which the improvements constituting the present invention are incorporated; Fig. 2 is a reverse side view of the thrust bar shown in Fig. 1; Fig. 3 is a plan view of the sinker ring on which cams are provided for swinging the thrust bar outward, and a cross section of the thrust bar on the line 3-3, Fig. 1; Fig. 4 is a fragmentary plan view of the pattern drum and a cross section of the thrust bar on the line 4-4, Fig. 1; and Fig. 5 is a diagrammatic side view of a high splice heel reinforcement such as the mechanism shown is specially designed to produce.

Referring more particularly to Fig. 1, 1 designates the rotary needle cylinder of a circular knitting machine of a well known type, such as the Scott and Williams machine. It is provided in the usual manner, with needles 2. A sinker ring or web-holder bed 5, is mounted on the upper end of the needle cylinder and provided with sinkers

or web-holders 6. A yarn guide 8, pivotally mounted on a pin 9 in an arched extension 10 of the latch guard ring 11 and spanning a radial slot therein, is movable at its inner lower end, as indicated by dotted and full lines, into and out of operative position for directing splicing yarn to the needles 2. The latch guard ring 11 is pivotally connected by a pin 12, with a post 13, rising from the stationary bed 14 on which the needle cylinder is rotatably mounted with a bevel gear 15 driven by the usual or any suitable mechanism (not shown).

A spring 17, tends to swing the yarn guide 8 downward from its elevated inoperative position, shown by full lines, into operative position, indicated by dotted lines, in which it rests on the throat plate 18, attached to the latch guard ring 11, and spanning the slot therein.

A pattern drum 20, with which machines of this type are provided, is located below the yarn guide 8 and bed 14, and is operated by the usual or any suitable actuating connections (not shown).

The parts thus far enumerated are common to circular knitting machines of the class referred to, and their construction and operation being well understood by those familiar with the art to which the present invention pertains, need not be more specifically described.

For the purposes of the present invention, the machine is provided with means for knitting splicing yarn with the main yarn into seamless tubular articles, such as hosiery, in partial courses of different lengths to form reinforcements such as a so-called high splice heel having narrower and wider portions. As shown by the drawing, such means comprises a longitudinally movable and laterally swinging thrust bar between the yarn guide 8 and pattern drum 20, for shifting the yarn guide out of operative position, cams of different lengths mounted on and rotatable with the sinker ring 3 in different horizontal planes for swinging the thrust bar outwardly during parts of successive revolutions of the needle cylinder and cams on the pattern drum 20 for shifting the thrust bar bodily into position to hold the yarn guide out of operative position and for shifting a part of the thrust bar from position to cooperate with one of the cams on the sinker ring into position to cooperate with the other.

The thrust bar, as shown, is composed of two sections or members 22 and 23, one of which is guided and movable lengthwise on the other.

5 The section or member 22 is slidably fitted in a channel formed in one side of the section or member 23, and is connected therewith and held in place by shouldered screws or studs 24 and 25, each passing through a 10 slot in one section and threaded or fastened in the other section. The section or member 22 is formed or provided with an inwardly projecting tipping abutment 26, opposite the sinker ring 3, and adjacent its 15 lower end with a lifting abutment 27, which may consist of a nut or roller on the screw or stud 25, as shown in Fig. 4.

The thrust bar is supported and guided in the usual way adjacent its upper and 20 lower ends, by combs 29 and 30, and pivots adjacent its lower end on the rounded surface of a transverse rod or bar 31 to which the comb 30 is fastened, so as to swing at its upper end in the comb 29 towards and from 25 the needle cylinder 1 and sinker ring 3. The member or section 23 projects at its upper end above the upper end of the section or member 22 into engagement with a cam or incline 34, formed on the under side of 30 the yarn guide 8. At its lower end the section or member 23 bears on the pattern drum 20.

A spring 36 connecting the sections or 35 members of the thrust bar with each other, tends to shift the section 22 downward and to hold it in its lower position on the section 23.

As shown by the drawing, the machine is 40 designed particularly for knitting seamless stockings with high splice heel reinforcements, comprising narrow upper portions *a*, and wider lower portions *b*, next to the heels, as shown in Fig. 5, but it may be adapted or used with little or no change, 45 for knitting other tubular or seamless articles with similar reinforcements or for knitting stockings with reinforced soles, as well as with high splice heels.

For the particular purpose above mentioned, the sinker ring 3 is provided with 50 two cams 38 and 39, of different lengths, located one above the other and adapted to cooperate with the abutment 26 in its upper and lower positions respectively, for swinging the thrust bar outward and shifting the 55 yarn guide 8 upward out of operative position, as shown by full lines in Fig. 1, during corresponding parts of successive revolutions of the needle cylinder 1.

60 The pattern drum 20 is provided with cams 40 and 41, for shifting the thrust bar bodily upward and holding the yarn guide 8 out of operative position during the operations of the machine in knitting the plain unreinforced portions and the heels of stock-

ings. It is also provided with a cam 42 for engagement with the lifting abutment 27, to shift the tipping abutment 26 on the section or member 22 of the thrust bar, upward, 70 into position to cooperate with the upper cam 38 for knitting the upper narrow portion *a* of the high splice heel reinforcement.

In the operation of the machine, while the lower end of the thrust bar rides on the cam 40, the knitting mechanism functions 75 in the usual way to knit the plain unreinforced portion of the leg of a stocking. As the thrust bar clears the trailing end of the cam 40, the pattern drum being rotated in the direction indicated by an arrow on Fig. 1, the yarn guide 8 is released by the thrust bar and turned downwardly by the spring 17 into operative position on the throat plate 18, and the tipping abutment 26 is shifted upward by engagement of the cam 42 with the lifting abutment 27, into position to cooperate with the upper and longer cam 38. While the abutment 27 rides on the cam 42, the cam 38 swings or tips the upper end of the thrust bar outward, and by its action on the cam or incline 34, shifts the yarn guide 8 out of operative position during corresponding parts of successive revolutions of the needle cylinder, the yarn guide being released and returned by the spring 17 into operative position during intervals of such revolutions of the needle cylinder corresponding with the distance between the ends of the cam 38. The splicing yarn is thus delivered to the needles 2 and 85 knit with the main yarn into the stocking in corresponding parts of successive courses, thereby forming the upper narrow portion *a*, as shown in Fig. 5, of the high splice heel reinforcement, the length of the narrow portion of the reinforcement vertically and the 90 number of courses into which it is knit, depending upon the variable intermittent movement of the pattern drum 20.

When the abutment 27 clears the cam 42, the tipping abutment 26 is shifted downward by the spring 36 into position to cooperate with the lower and shorter cam 39, and the yarn guide 8 is in like manner shifted and held by the thrust bar out of operative position during shorter intervals or partial successive revolutions of the needle cylinder, and the splicing yarn is delivered to the needles and knit into the stocking in longer 105 partial courses, which correspond in length to the distance between the ends of the cam 39, to produce the wider and usually much shorter lower portion *b*, of the reinforcement next to the heel.

When the heel reinforcement is completed, the cam 41 by engagement with the thrust bar, lifts the yarn guide 8 and holds it out of operative position during the knitting of the heel.

If desired, the same splicing yarn may be 110 115 120 125 130

knit into the sole of the stocking to form a reinforcement *c*, as shown in Fig. 5, between the heel and toe, by a proper arrangement of cams on the pattern drum 20.

5 Various modifications in the construction and arrangement of parts of the mechanism for knitting splicing yarn into seamless stockings or other tubular knitted articles, to adapt the mechanism to circular knitting
10 machines of different makes or designs, and to produce reinforcements of different widths and different lengths, may be made without departure from the principle and scope of the invention as defined in the following claims.

I claim:

1. In a knitting machine the combination with a rotary needle cylinder provided with needles, a yarn guide movable into and out

20 of operative position to direct splicing yarn to the needles, and a pattern drum, of a laterally swinging bar movable towards and from the needle cylinder and adapted when swung outwardly to shift the yarn guide out

25 of operative position, an abutment mounted on and movable lengthwise of said bar, cams of different lengths connected and rotatable with the needle cylinder in different horizontal planes and adapted by engagement

30 with said abutment to swing and hold said bar outward during parts of successive revolutions of the needle cylinder, and a cam on the pattern drum adapted to shift said abutment from one of its operative po-

35 sitions to the other.

2. In a knitting machine the combination with a rotary needle cylinder provided with needles, a yarn guide movable into and out of operative position to direct splicing yarn

40 to the needles, and a pattern drum, of a longitudinally and laterally movable thrust bar adapted when moved lengthwise upward or swung outward, to shift the yarn guide out of operative position, an abutment

45 mounted on and movable lengthwise of the thrust bar, cams of different lengths connected and rotatable with the needle cylinder in different horizontal planes, and each adapted by engagement with said abutment

50 to swing and hold the thrust bar outward during parts of successive revolutions of the needle cylinder, a cam on the pattern drum adapted to shift said abutment from position to cooperate with one of the two first

55 cams into position to cooperate with the other, and another cam on the pattern drum adapted to shift said thrust bar upward at a predetermined point in the operation of the machine and to hold it out of operative

60 position during the knitting of a certain number of courses.

3. In a knitting machine the combination with a rotary needle cylinder provided with needles, a yarn guide movable into and out

65 of operative position to carry splicing yarn

to the needles, and a pattern drum, of a longitudinally movable and laterally swinging thrust bar composed of sections one of which is mounted and movable lengthwise on the other and is provided with a tipping 70 abutment and a lifting abutment, cams of different lengths rotatable with the needle cylinder in different horizontal planes and each adapted by engagement with said tipping abutment to swing and hold said bar 75 outward in position to hold the yarn guide out of operative position during corresponding parts of successive revolutions of the needle cylinder, and a cam on the pattern drum adapted by engagement with said lifting abutment to shift the tipping abutment from a position to cooperate with one of the first two cams into position to cooperate with the other.

4. In a knitting machine the combination 80 with a rotary needle cylinder provided with needles, a yarn guide movable into and out of position to carry splicing yarn to the

needles, and a pattern drum, of a longitudinally movable and laterally swinging 85 thrust bar composed of sections one of which is mounted and movable lengthwise on the other and is provided with a tipping abutment and with a lifting abutment, cams of

90 different lengths rotatable with the needle cylinder in different horizontal planes and each adapted by engagement with said tipping abutment to swing said bar outward and to hold it in position to hold the yarn

95 guide out of operative position during corresponding parts of successive revolutions of the needle cylinder, a cam on the pattern drum adapted by engagement with said lifting abutment to shift the tipping abutment from a position to cooperate with one

100 of the two first cams into position to cooperate with the other, and another cam on the pattern drum adapted by engagement with the thrust bar to shift it upward into

105 position to hold the yarn guide out of operative position.

5. In a knitting machine the combination with a rotary needle cylinder provided with needles, a pivoted yarn guide movable into and out of operative position to carry splicing yarn to the needles, and provided with a

110 cam, a spring tending to shift the yarn guide downward and hold it in operative position, and a pattern drum, of a longitudinally movable and laterally swinging thrust bar located between the yarn guide and pattern

115 drum and composed of two members one of which is guided and movable lengthwise on the other and is provided with a tipping abutment adjacent the needle cylinder and with a lifting abutment adjacent the pattern

120 drum, a spring tending to shift the abutment member of the thrust bar downward, cams of different lengths rotatable in different horizontal planes coaxially and

125 130

5 synchronously with the needle cylinder and each adapted by engagement with said tipping abutment to swing the thrust bar outward and hold it in position to hold the yarn guide out of operative position during parts of successive revolutions of the needle cylinder, the yarn guide spring tending to swing the thrust bar inward by engagement of the yarn guide cam with said bar, and

10 a cam on the pattern drum adapted by engagement with the lifting abutment to shift the tipping abutment upward from position to cooperate with one of the cams coaxial with the needle cylinder into position to cooperate with the other.

15 In witness whereof I hereto affix my signature.

JOSEPH H. ZENS.
